FIG. 1.

INVENTOR

E. Carney
BY
Dwight, Warfield & Dwelt
ATTORNEYS

UNITED STATES PATENT OFFICE.

EDWARD CARNEY, OF GLENDALE, NEW YORK, ASSIGNOR TO EASTERN SALES BOOK COMPANY, OF GLENDALE, NEW YORK, A CORPORATION OF NEW YORK.

MANIFOLDING DEVICE.

1,075,460.

Specification of Letters Patent.

Patented Oct. 14, 1913.

Application filed April 14, 1911. Serial No. 620,979.

To all whom it may concern:

Be it known that I, EDWARD CARNEY, a subject of the King of England, residing at Glendale, in the county of Queens and State 5 of New York, have invented certain new and useful Improvements in Manifolding Devices, of which the following is a full, clear, and exact description, such as will enable others skilled in the art to which it appertains to make and use the same.

This invention relates to the duplication of marks made upon paper or like material, and with respect to its more specific features to triplicating sheets adapted to be used in 15 connection with a single transfer sheet.

One of the objects of the invention is to provide a practical and efficient device of the type described in which the original impression and the copies thereof may all be made 20 upon substantial and durable paper.

Another object is to provide a simple and durable device of the kind described in which the copy impressions will have clear and distinct markings.

25 Another object is to provide a device of the type described which will be easy to handle and cheap to manufacture.

Other objects will be in part obvious and in part pointed out hereinafter.

30 The invention accordingly consists in the features of construction, combinations of elements and arrangement of parts which will be exemplified in the construction hereinafter set forth, and the scope of the application of which will be indicated in the following claims.

In the accompanying drawing forming part of this specification and in which similar reference numerals refer to similar 40 parts throughout the several views, Figure 1 is a perspective view of one of the possible embodiments of the invention, and Fig. 2 is an edge view thereof.

Although the general characteristics and 45 the desirable features of the invention are clearly shown in the embodiment represented in the drawing it is believed that it will tend to a clearer and more complete appreciation thereof to point out some of its 50 characteristic and progressive features.

The use of triplicate sheets as bills of lad-

ing, in connection with sales books, etc., is becoming more desirable with the advance of the systems of checking, auditing, etc., employed by the business concerns of the present day. Under the ordinary conditions 55 of use, a sheet of this character must give strong and permanent records which will resist the wear attendant upon their use by clerks, truckmen, and others, who must work rapidly and without troublesome precautions 60 concerning the weakness of any part of the sheet itself, holding means, or other associated parts. That applicant meets these requirements and provides a device which possesses many other desirable features will 65 be apparent by referring to the embodiment shown in the drawing.

A cover 1, provided with fastening means 2 holds a pad 3. The pad comprises a plurality of single sheets superimposed to form 70 a pile and joined together by pins or staples 4 passing through a stub portion 5. Each sheet is preferably integral, and is divided into three rectangular sections of substantially equal size by folding or transverse 75 weakening lines arranged parallel to the ends of the sheet. According to this construction each sheet comprises a section forming part of the stub portion and another section extending laterally thereof and adapted to be folded upon the first section. The sheets may be composed of various materials and are preferably flexible. The middle section 6 of the sheet is adapted to receive on its reverse side, that is, on the 80 opposite side to that shown in the drawing, an original impression or marking which may be made in any of the usual ways, by a pencil, marking machine, or other device. The original marking made upon section 6, 85 when in operative position, is adapted to be transmitted to both of the end sections 7 and 8 and there recorded by means of a transferring agent, preferably a double-faced carbon paper 9. To bring the sheets into operative relation, the carbon paper 9 is placed upon the pile in a position resting upon section 8. Section 7 being in its normal position superimposed upon section 6, sections 6 and 7 are swung and folded about the weakening line 11 until they occupy a superim-

posed relation with respect to section 8 and the superimposed carbon sheet 9. When all of the sections and carbon paper are thus placed in superimposed relation, if a mark 5 be made upon the surface of section 6, the reverse side of which will at that time be uppermost, one face of the carbon paper 9 will simultaneously make a copy upon that portion of section 7 which lies contiguous thereto and the other face of the carbon 10 paper will simultaneously transfer a copy of the mark to the face of section 8. The impression made upon the back of section 7 will show the marking, whether it be writing or otherwise, in a position reversed with 15 respect to the original marking. The sheet 7 is consequently treated to render it translucent, whereby a mark made on one side thereof may be seen from the other side in 20 the same position as it occupied upon the original, in this instance section 6. In this way a substantial durable record is made on the three sections. It has been found preferable in rendering section 7 translucent to 25 impregnate it with a suitable oil. The oil may have various properties, but should be present in such proportion and possess such consistency that it will be readily retained in the pores of the paper to prevent a soiling of any articles or material with which 30 the section may be brought in contact. It will be seen that the durable material of which each sheet is composed will be rendered translucent by the treatment described, and that the untreated portions or sections 35 of the material will consequently be opaque relative to said translucent section. As the material ordinarily employed in manifolding devices is a thin paper which transmits light to a certain degree and is not technically opaque, applicant refers to the material employed by him as relatively opaque, in order to include such thin materials as well 40 as technically opaque material.

45 In the embodiment shown, the carbon leaf is attached to a piece of stiff paper or like material 12 and is held removably between cover 1 and pad 3, and extends out to one side of the pad, being of such size that it 50 may be readily overlapped, upon the section 8.

55 Although in the embodiment shown in the drawing the section 8 is attached along its upper edge to the stub-portion 5, it is to be understood that the point of attachment may be along one of the other edges or may occupy any other suitable position. It is further to be observed that a weakening line 60 13 may be disposed between the section 8 and the stub-portion or it may be omitted if desired.

65 After the original impression or marking has been made and the copies thereof secured, it is frequently necessary to detach the sections of the sheet in order that one

or more may be sent to various departments or offices, etc. This detachment may be easily accomplished by tearing the paper along the weakening lines 10 and 11.

70 Although the triplicating sheets have been described in connection with a pad, it is to be understood that they may be used separately and unattached as bills of lading, sales slips, etc.

75 It is to be noted in connection with the device that a plurality of copies is simultaneously secured with the marking of an original sheet by means of a single carbon sheet which employs simply two active transfer surfaces. This feature not only 80 provides an economy in carbon paper, but also secures a simplicity of operation and a saving of time.

85 It will thus be seen that a simple device is provided wherein the objects of the invention, among others, are achieved.

90 It is to be understood that although the pad has been shown in connection with a counter sales book that it may embody as well the various forms of slips and sheets used as bills of lading, etc., as previously mentioned in this specification.

95 As many changes could be made in the above construction and many apparently widely different embodiments of this invention could be made without departing from the scope thereof, it is intended that all matter contained in the above description or shown in the accompanying drawings shall be interpreted as illustrative and not in a 100 limiting sense. It is also to be understood that the language used in the following claims is intended to cover all of the generic and specific features of the invention herein described, and all statements of the scope 105 of the invention which, as a matter of language, might be said to fall therebetween.

110 Having described my invention, what I claim as new and desire to secure by Letters Patent is:

1. A manifolding device comprising an integral sheet of durable material adapted to be folded to place portions thereof in superposed relation, one of said durable portions being relatively opaque and another of said durable portions translucent.

115 2. A manifolding device comprising an integral sheet of durable material adapted to be folded to place portions thereof in superposed relation, one of said durable portions being relatively opaque and another of said durable portions oiled to render it translucent.

120 3. A manifolding device comprising, in combination a pile of sheets of durable material divided into sections, the sections of each sheet being integral with each other, one of said durable sections of each sheet being relatively opaque and another of said durable sections oiled to render it trans- 125

lucent relative to said opaque section, each sheet adapted to be folded to place said opaque section in superposed relation to said oiled section, said oiled sections being 5 similarly disposed in the pile, and material adapted to be interposed between said opaque and oiled section of each sheet when superposed to transfer impressions to each.

In testimony whereof I affix my signature, in the presence of two witnesses.

EDWARD CARNEY.
